UNITED STATES PATENT OFFICE.

THEODORE A. GLENDE AND WILLIAM B. FRANKENSTEIN, OF ROCHESTER, NEW YORK,
ASSIGNORS TO PRITCHARD STAMPING COMPANY, OF ROCHESTER, NEW YORK, A
CORPORATION OF NEW YORK.

TUBULAR LANTERN.

1,189,249.

Specification of Letters Patent.

Patented July 4, 1916.

Application filed October 8, 1915. Serial No. 54,898.

To all whom it may concern:

Be it known that we, THEODORE A. GLENDE and WILLIAM B. FRANKENSTEIN, citizens of the United States, and residents 5 of Rochester, in the county of Monroe and State of New York, have invented certain new and useful Improvements in Tubular Lanterns, of which the following is a specification.

10 This invention relates particularly to a tubular lantern in which wire members such, for example, as the slide-guides controlling the globe-cage, are secured to the air-tubes, and the object of the invention is 15 to produce a simple and strong construction for securing such wire members to the tubes, and particularly to accomplish this without the use of solder.

To the foregoing end we employ the 20 construction hereinafter described and illustrated in the accompanying drawings.

In the drawings:—Figure 1 is a partial front-elevation of a lantern embodying the present invention; Fig. 2 is a perspective 25 view showing, in detail, a portion of one of the air-tubes with a wire slide-guide fixed thereto in the manner of the present invention; and Fig. 3 is a horizontal section through the parts shown in Fig. 2.

30 The invention is shown as applied to, or embodied in, a tubular lantern of a well-known form, this lantern having the usual air-tubes 5 and globe 6. The globe is mounted in a cage or frame comprising 35 side-wires 7, and these side-wires engage and coöperate with slide-guides 8, of which the general form is shown particularly in Fig. 2 and is not novel. The invention is illustrated particularly as embodied in the 40 connection between each slide-guide 8 and the corresponding air-tube. For this purpose the tube is provided, on either side of its central vertical wall 9, with a pair of perforations 10, 11, arranged in vertical 45 relation, and between these two perforations the sheet-metal is pressed outwardly to form a channel or offset 12 extending beyond the body of the tube. The slide-guide is provided with a straight portion 13, near each 50 end, which lies in the offset 12, as shown particularly in Fig. 3. To prevent longitudinal movement of the wire in the offset it is provided with a short bend 14 just above each upper perforation 10, this bend

serving to prevent the wire from sliding 55 downwardly. To prevent the wire from sliding upwardly its lower extremities are bent back and upwardly, so as to closely embrace the offset 12. Since the pressure of the slide-wires 7 against the slide-guides 60 tends to force the latter toward the tubes 5, each guide is provided, just above the bend 14, with a reverse bend which constitutes an abutment adapted to rest against the outer surface of the air-tube and thus resist 65 the pressure.

Prior to assembling the parts the slide-guide is made complete as shown, except that the extremities 15 are in a straight line with the parts 13. The ends of the wire are 70 then passed downwardly into and through the perforations 10 and 11, and it is then necessary only to bend up the extremities 15 in order to complete the structure. Owing to the complete interlocking of the 75 parts it is unnecessary to use any solder in fixing them together, and the construction of the lantern is thus cheapened without the sacrifice of strength.

The outward offsetting of the metal be- 80 tween the perforations in the air-tube is an important feature of the present invention, since it permits the slide-guide to be inserted and locked in place by operations performed wholly from the exterior of the 85 air-tube, and without the necessity of providing perforations of a diameter any greater than that of the wire which is introduced. We are aware that, in a lantern of the railroad type, it has been previously 90 proposed to fix the guard-wires in place by passing them through perforations in the body of the lantern, but in such proposed constructions the guard-wires, when introduced, have been bent or provided with lugs 95 or lateral projections, so that in introducing them it has been necessary either to use unduly large perforations, or to sever the metal of the body on a line between the perforations, or to introduce the wires by 100 an angular movement, such as is not practicable in the case of the slide-guide of the present invention.

While the construction above described is particularly useful in connection with 105 slide-guides of the kind referred to, it will be apparent that it may be employed in connection with other wire members which

it may be necessary to secure to the air-tubes.

We claim:—

1. In a tubular lantern, the combination 5 of an air-tube having a pair of perforations, and the metal between the perforations unbroken but outwardly offset from the body of the tube; and a wire slide-guide having a straight part lying in said perforations 10 and said offset, an outward bend engaging the end of the offset, an inward bend engaging the body of the air-tube beyond the offset, and a portion, beyond said inward bend, adapted to perform the function of 15 a slide-guide.
2. In a tubular lantern, the combination of an air-tube having, on each side of the middle of its inner surface, a pair of vertically spaced perforations, and the metal be-

tween the perforations being unbroken but 20 outwardly offset from the body of the tube; and a wire slide-guide having two parallel end-portions which extend through said perforations and lie in said offsets.

3. In a tubular lantern, the combination 25 of an air-tube having, on each side of the middle of its inner surface, a pair of vertically spaced perforations, and the metal between the perforations being unbroken but outwardly offset from the body of the tube; and a wire slide-guide having two parallel 30 end-portions which extend through said perforations and lie in said offsets, each end being bent both above and below the corresponding offset so as to secure the 35 wire in place without soldering.

THEODORE A. GLENDE.

WILLIAM B. FRANKENSTEIN.
